UNITED STATES PATENT OFFICE

FRITZ C. STETTER, OF IRVINGTON, NEW JERSEY, ASSIGNOR TO SIMON MILLER & CO., OF NEWARK, NEW JERSEY, A COPARTNERSHIP COMPOSED OF MORRIS MILLER AND EMANUEL MILLER

DESIGN FOR A LINK BRACELET

Application filed October 25, 1930. Serial No. 37,391. Term of patent 7 years.

To all whom it may concern:

Be it known that I, FRITZ C. STETTER, a citizen of the Republic of France, a resident of Irvington, in the county of Orange and State of New Jersey, U. S. A., have invented a new, original, and ornamental Design for Link Bracelets, of which the following is a specification, reference being had to the accompanying drawings, forming part thereof.

Fig. 2 is an enlarged fragmentary outer side elevation of a bracelet on an enlarged scale.

Fig. 3 is a transverse sectional view taken on the line 3—3 of Fig. 4; and

Fig. 4 is a detail elevation of one of the bracelet links shown in Fig. 2.

I claim:—

The ornamental design for a link bracelet, as shown.

FRITZ C. STETTER.
